UNITED STATES PATENT OFFICE.

JACOB RHULE, OF PITTSBURG, PENNSYLVANIA, ASSIGNOR OF TWO-THIRDS TO SYLVESTER A. COSGRAVE AND CHARLES W. SCOVEL, BOTH OF SAME PLACE.

CAR-COUPING.

SPECIFICATION forming part of Letters Patent No. 387,999, dated August 14, 1882.

Application filed December 23, 1887. Serial No. 238,804. (No model.)

To all whom it may concern:

Be it known that I, JACOB RHULE, of Pittsburgh, in the county of Allegheny and State of Pennsylvania, have invented a new and 5 useful Improvement in Car-Couplings, of which the following is a full, clear, and exact description.

This invention is in the nature of an improvement on the car-coupling for which Letters Patent of the United States, No. 278,598, were issued to me May 29, 1883.

The object of this improvement is to adapt the said car-coupling for use with opposing draw-heads of different lengths, and to 15 strengthen and stiffen the depending draft-plate which resists the strain on the draw-bar, and the angular brace by which said draft-plate is sustained.

The invention comprises certain novel 20 details of construction and combinations of parts, hereinafter fully described, and distinctly pointed in the claims.

Reference is to be had to the accompanying drawings, forming a part of this specification, 25 in which similar letters of reference indicate corresponding parts in all the figures.

Figure 1 is an inverted plan view of a part 30 of a car-bottom frame provided with a car-coupling embodying my present invention. Fig. 2 is a longitudinal sectional elevation of the same on the line $x-x$, Fig. 1. Fig. 3 is a detail perspective view of the improved draft-plate and sustaining-brace. Fig. 4 is a detail perspective view, and Fig. 5 is a sectional view, 35 of a part hereinafter described.

The draw-head A, its lining B, and keeper C, the draw-bar D, draft-plate E, cushioning-springs F and G, and angular draft-sustaining brace H are or may be arranged substantially 40 as described in my previous application, No. 278,598, before referred to.

To adapt the one size of draw-head, A, for use with opposing draw-heads of different lengths a strong spool, J, preferably of cylindrical form, as shown, is placed on the draw-bar D between the draft-plate E and the rear of the draw-head, and in this instance in front of the buffer-spring F, said spool being of such length as to make the draft or travel 45 of the draw-head the same as that of the op-

posing draw-head. The end of said spool facing the spring F is formed with a concave socket, J', as shown in Figs. 4 and 5, to receive and hold the end of the spring.

The draft-plate E is strengthened with respect to the angular brace H by brackets K, which are bent down from the body of the brace parallel with each other, and so as to coincide with the inner edges of the two central longitudinal floor-beams, L, thus permitting fastening-bolts M to be passed through each brace-arm adjacent to the brackets K, near both edges of said arm. The draft-plate E, being thus strongly braced, is re-enforced by a flat plate, N, welded or riveted to its outer 65 face to resist the direct strain caused by the draw-bar. The two diverging arms of the angular brace are connected near the bolster O, to which their rear downturned ends are bolted by a transverse rigid T or like bar, P, 70 the ends of which are secured to the brace-arms by the bolts Q, which pass also through the corresponding longitudinal beams L. The bar P relieves the bolts connecting the brace with the bolster of excessive strain while 75 greatly stiffening the arms of the brace laterally.

Having thus fully described my invention, I claim as new and desire to secure by Letters Patent—

1. In a car-coupling, the combination, with a draft-plate fixed to the car-body, a sliding draw-head, a draw-bar working loosely in the draft-plate and the draw-head and having end stops, cushioning-springs on the draw-bar between its rear end stop and the draft-plate and between the draw-head and the draft-plate, respectively, of a spool placed loosely on the draw-bar between the draw-head and the draft-plate, substantially as described. 85

2. In a car-coupling, an angular metallic draft-sustaining brace having its end at the apex of the angle bent downward at a right angle and apertured to form a transverse draft-plate, and the metal at opposite sides of 95 said draft-plate bent downward to form parallel strengthening-brackets at right angles thereto, substantially as described.

3. The combination, with the longitudinal beams of a car-bottom and the bolster, of an 100

angular brace carrying a draft-plate, bolts connecting the ends of said brace with the bolster, a rigid transverse bar bridging the angular brace, and bolts each passing through 5 an end of the transverse bar, the corresponding arm of the brace, and the longitudinal car-beam thereabove, substantially as described.

4. In a car-coupling, an angular draft-sus-

taining brace having its forward angle end 10 bent down to form a draft-plate, in combination with a re-enforcing plate welded or riveted to the outer face of the draft-plate, substantially as described.

JACOB RHULE.
